(57) CLAIM

The ornamental design of the key shaped key clip design for permitting key rings and the like to be attached thereto, as shown and described.

DESCRIPTION

FIG. 1 is a perspective view of one embodiment of the key shaped key clip design for permitting key rings and the like to be attached thereto of this invention.

FIG. 2 is a front elevation horizontal view of the key shaped key clip design for permitting key rings and the like to be attached thereto of FIG. 1.

FIG. 3 a rear side elevation horizontal view of the key shaped key clip design for permitting key rings and the like to be attached thereto of FIG. 1.

FIG. 4 is a side view elevation of the key shaped key clip design for permitting key rings and the like to be attached thereto of FIG. 2.

FIG. 5 is a bottom end elevation view of the key shaped key clip design for permitting key rings and the like to be attached thereto of FIG. 4; and,

FIG. 6 is a top end elevation view of the key shaped key clip design for permitting key rings and the like to be attached thereto of FIG. 4.
